UNITED STATES PATENT OFFICE

LEE S. CHADWICK, OF SHAKER HEIGHTS, OHIO.

VIBRATING APPARATUS.

Application filed April 6, 1928. Serial No. 267,829.

This invention relates to an improved vibrating machine suitable for use in homes, gymnasiums, doctors' offices, sanitariums, and like places, for exercising and massaging various parts of the body, and it pertains more especially to that class of vibrating machines involving an applicator band or strap that is adapted to be engaged about the part of the body that is to be treated, and mechanism for 10 vibrating the band or strap by imparting to it in rapid succession quick jerks in opposite directions.

Among the objects of the invention are the production of a machine of the above nature that is highly efficient, yet very simple of construction and relatively inexpensive; that is compact; that is preferably designed for attachment to a wall or other vertical supporting surface, though the invention is susceptible to incorporation in a structure that may stand upon the floor; that involves simple means for changing the length of the stroke of the applicator strap so that its action may be rendered suitable for the requirements of 25 different individuals, or better adapted to the treatment of the different parts or members of the body, it being evident that a shorter and more gentle stroke is required for the treatment of the neck, for example, than is required for effective treatment of the arms 30 or legs, shoulders, back and other such parts of the body.

The invention contemplates the use of a vibrating bar that is pivotally supported intermediate its ends for oscillation on a substantially vertical axis, and the applicator strap or band has its respective ends suitably connected to the vibrating bar on opposite sides of the latter's pivotal axis.

A further object of the invention is to provide means for facilitating like adjustment of the connections between the ends of the applicator strap and bar on opposite sides of, and with respect to, the latter's oscillating axis; and, further, to provide means for simultaneously effecting adjustment of the connections associated with the two ends of the strap.

Other and more specific objects of the invention will appear as I proceed to describe the embodiments of the invention herein dis-

closed by reference to the accompanying drawings, wherein Fig. 1 represents a front elevation, and Fig. 2 a plan view, of a vibrating machine constructed in accordance with the invention; Figs. 3, 4, 5 and 6 are sectional details on the respective correspondingly numbered lines of Fig. 2; Figs. 7 and 8 are, respectively, a fragmentary front elevation, and a plan view, of a modification of the invention; Fig. 9 is a sectional detail on the line 9—9 of Fig. 7; Fig. 10 is a plan view of a further modified form of the invention; and Fig. 11 is a detail.

According to the present disclosure, the machine is constructed for attachment to a wall or other vertical support, and the same includes a base 1 that is adapted to be secured, as by screws or bolts 2, to a wall or other like support, and suitably fastened to the base adjacent the right hand side thereof, and arranged with its shaft vertical, is an electric motor 3 having a relatively small pulley 4 secured to the lower end of its armature shaft. Journaled in bearings 5 that are supported by and forwardly of the left hand side of the base 1 is a jack shaft 6 that has a relatively large pulley 7 fastened to its lower end, and a belt 8 is engaged about said pulley and the previously mentioned pulley 4. A crank disk 10 is fastened to the upper end of the shaft 6.

Bearings 12 and 13 are supported by and forwardly of the upper end of the base 1, and journaled within these bearings is a rock shaft 14 to which the hub of an arm 15 is pinned or otherwise secured between said bearings, and a link 17 connects the free end of said arm with a crank pin 18 on the previously mentioned disk 10.

Fixed to the upper end of the rock shaft 14 is a head 20 that carries a vibrating bar 21. In the present embodiment, this bar consists of a relatively heavy cylindrical member that is fixed in the head 20, and slidable along the bar on opposite sides of said head are blocks 22. Keys 23, that are set within the blocks 22, engage within a keyway 24 in the bar so that while said blocks are capable of being adjusted lengthwise of the bar they are held against angular movement with respect thereto. A pulley 25 is

carried by each end of the bar, and a flexible element 26, which may consist of a steel band, a leather strap, or a length of belting or like material, is fastened to the rear side of each block 22 and is carried therefrom over the pulley 25 that is located beyond the adjacent end of the bar 21 and back past the block to which it is secured, across the front face of the head 20 and has its opposite end fastened to the other block 22. By reason of this connection between the two blocks, both are moved inwardly or outwardly a like distance along the opposite end portions of the bar 21 when either one of the blocks is manually shifted to different positions on the bar. A cover plate 30 is applied to the recessed front surface of the head 20 and the flexible elements 26 pass between it and the depressed front surface of said head; and a locking screw 31 is threaded through the plate 30, and on its inner end is swiveled a shoe 32 between which, and the opposed surface of the head 20, the flexible elements 26 are adapted to be clamped when said screw is turned inwardly by means of its hand wheel 33.

A yielding connection may be provided between each of the pulleys 25 and the vibrating bar 21 to take up slack that may occur in the flexible elements 26, and in the present instance this is effected by extending shanks 35 of the pulley hangers 36 into bores in the ends of the bar 21, and by disposing compression springs 37 between the inner ends 38 of said shanks and the bottoms of said bores. The bar is slotted in the region of said shanks, and screws or pins 38 are engaged through said slots and driven into the shanks for holding the pulley hangers against rotation and for preventing their shanks from being projected from the bores when, for any reason, the flexible elements are disengaged from the pulleys.

40 designates the applicator strap or band, 45 and its looped ends 41 are engaged over hooks 42 that are carried by the blocks 22.

The electric motor 30 is supplied with current through suitable conductors (not shown), and the circuit of the motor includes 50 a switch 45 that may be mounted on the base 1 alongside the motor. When the switch is closed and the motor thus set in operation it drives the jack shaft 6 through the belt connections already described and as the disk 10 that is carried by said shaft is rotated it vibrates the bar 21 through its connection therewith consisting of the crank pin 18, link 17, arm 15 and rock shaft 14.

60 The user engages the applicator strap 40 about the part of the body that is to be exercised or massaged and draws said strap taut so that the vibrations of the arm 21 are imparted through the strap to the body. If he desires to alter the stroke of the applicator 65 strap, he releases the locking screw 31 and

slides one of the blocks 22 along the vibrating bar until the desired length of stroke is attained, the other block being simultaneously shifted a like distance from the center of oscillation of the vibrating arm through the medium of the flexible elements 26. When the desired adjustment is obtained, the locking screw 31 is tightened to hold the blocks, through means of said flexible elements, in their new positions. 75

Figs. 7, 8 and 9 illustrate a modified construction in which the vibrator arm consists of a flat bar, the same being designated 45. This bar is secured, as by screws 46, to a head 47 on the rock shaft designated, as in the former case, 14. Slots 48 extend longitudinally of the bar 45 on opposite sides of its center of oscillation, and at like distances along each of the slots are circular openings 49. A member 50 is adjustable along each of the slots 48, and it includes a neck 51 that is cylindrical and of a diameter to fit the circular openings 49, excepting for the fact that its sides are flattened and are spaced apart a distance substantially equal to the width of the slot. As a consequence of this construction, when the member is turned to dispose the flattened sides of its neck parallel with the axis of the slot, the member may be shifted along the slot, but it may be turned at an angle to this position when it occupies any one of the holes 49, and when so turned it is held against movement along the slot. Hooks 53 are secured to the members 50 for the attachment of the looped ends of the applicator strap 40. 100 It is evident from this description that the hooks 53 may be adjusted toward and from the center of oscillation of the bar 45 to adjust the stroke of the strap. 105

A still simpler form of vibrating bar is illustrated in Fig. 10 where slides 55 are adapted to be adjusted along the bar 56 and held in any adjusted position thereon by means of set screws 57. Hooks 58 are carried by the slides 55 for the attachment of the looped ends of the applicator strap. To facilitate like adjustment of the two slides 55, the opposite ends of the vibrating bar are shown as set off in like spaces by indicating marks designated 59. 110

Referring again to the first described form of the invention, and with respect to means for taking up any slack that may occur in the flexible elements 26: in lieu of yieldingly mounting the pulleys 25 as hereinbefore explained, an adjustment, which may be in the nature of the well known turn-buckle, may be incorporated in each of the elements 26, or the elements may be adjustably connected to the blocks 22 that carry the applicator strap hooks, as illustrated in Fig. 11. As here shown, the block 22 has a lug 60 within which a screw 61 is mounted for free rotation, and the screw is extended through an opening in a stirrup 62 and threaded into a nut 63 that is 120 125 130

confined within said stirrup, the stirrup being secured, as by rivets 64, to the adjacent end of the corresponding flexible element 26.

It should also be explained that vacuum cup and so-called "spade handle" applicators are commonly used with machines of this character, and in the use of such applicators the stroke adjustment provided by my invention is especially advantageous, as it enables the user to obtain just the degree of action required in his or her particular case.

Having thus described my invention, what I claim is:—

1. In a vibrating machine, the combination of a vibrating bar, mechanism for actuating the same, members movable along the bar on opposite sides of its center of oscillation, guides carried by the bar outwardly beyond the range of movement of said members, two flexible elements engaged, respectively, with said guides each having its opposite ends connected, respectively, to the opposed members whereby said members, when adjusted, are caused to move simultaneously like distances in opposite directions, means for securing the members in various adjusted positions along the bar through the instrumentality of said elements, and means for connecting the opposite ends of an applicator strap to said members.

2. In a vibrating machine, the combination of a vibrating bar, members movable along said bar on opposite sides of its center of oscillation, a guide adjacent each end of the bar, two flexible elements each having one of its ends secured to one of said members and engaged over the guide at the adjacent end of the bar and its opposite end connected to the other member whereby simultaneous and like adjustment of the two members is adapted to be effected, and means for connecting the opposite ends of an applicator strap to said members.

3. In a vibrating machine, the combination of a vibrating bar, members movable along said bar on opposite sides of its center of oscillation, a guide adjacent each end of the bar, two flexible elements each having one of its ends secured to one of said members and engaged over the guide at the adjacent end of the bar and its opposite end connected to the other member whereby simultaneous and like adjustment of the two members is adapted to be effected, means for locking the members in various positions to which they are adjusted through the instrumentality of said flexible elements, and means for connecting the opposite ends of an applicator strap to said members.

4. In a vibrating machine, the combination of a vibrating bar, members movable along said bar on opposite sides of its center of oscillation, a guide adjacent each end of the bar, two flexible elements each having one of its ends secured to one of said mem-

bers and engaged over the guide at the adjacent end of the bar and its opposite end connected to the other member whereby simultaneous and like adjustment of the two members is adapted to be effected, means for taking up slack in said flexible elements, and means for connecting the opposite ends of an applicator strap to said members.

5. In a vibrating machine, the combination of a vibrating bar, members movable along the bar on opposite sides of its center of oscillation, means for connecting the respective ends of an applicator strap to said members, a guide adjustably carried by each end of the bar, and flexible elements each of which has one of its ends connected to one of said members and engaged about the guide of the corresponding end of the bar and its opposite end secured to the other of said members.

6. In a vibrating machine, the combination of a vibrating bar, members movable along the bar on opposite sides of its center of oscillation, means for connecting the opposite ends of an applicator strap to said members; a guide adjustably carried by each end of the bar, means urging the guides outwardly, and flexible elements each of which has one of its ends connected to one of said members and engaged about the guide at the adjacent end of the bar and its opposite end secured to the other of said members.

7. In a vibrating machine, the combination of a vibrating bar, mechanism for actuating the same, members movable along the bar on opposite sides of its center of oscillation, guides carried by the bar outwardly beyond the range of movement of said members, two flexible elements engaged, respectively, with said guides each having its opposite ends connected, respectively, to the opposed members whereby said members, when adjusted, are caused to move simultaneously like distances in opposite directions, means for securing the members in various adjusted positions along the bar, means for taking up slack in said flexible elements, and means for connecting the opposite ends of an applicator strap to said members.

8. In a vibrating machine, the combination of an oscillating shaft having a head provided with a cylindrical opening, a cylindrical vibrating bar engaged through the opening of the head and supported therein at about its longitudinal center, said bar having a keyway, a key attached to said head and occupying the keyway of the bar, members slidably engaged on the opposite end portions of the bar and equipped with keys operating within the keyway of the bar, mechanism for oscillating the aforesaid shaft, and means for connecting the opposite ends of an applicator strap to said members.

9. In a vibrating machine, the combination of an oscillating shaft having a head pro-

vided with a cylindrical opening, a cylindrical vibrating bar engaged through the opening of the head and supported therein at about its longitudinal center, said bar having a keyway, a key attached to said head and occupying the keyway of the bar, members slidably engaged on the opposite end portions of the bar and equipped with keys operating within the keyway of the bar, 5 mechanism for oscillating the aforesaid shaft, means for connecting the opposite ends of an applicator strap to said members, guides carried by the ends of the vibrating bar, two flexible elements each having one of its ends 10 secured to one of said members and engaged over the guide carried by the adjacent end of the bar and its opposite end secured to the other member, and means carried by the aforesaid head for securing the flexible elements against movement.

10. In a vibrating machine, the combination of an oscillating shaft having a head, a vibrating bar supported at about its longitudinal center by said head, clamping 15 means carried by the head, members reciprocable along the end portions of the vibrating bar, guides carried by the ends of the bar, two flexible elements each having one of its ends secured to one of said members and 20 engaged about the adjacent guide and through said clamping means and its opposite end secured to the other of said members, means for oscillating the aforesaid shaft, and means for connecting the opposite ends of an 25 applicator strap to said members.

In testimony whereof, I hereunto affix my signature.

LEE S. CHADWICK.
